UNITED STATES PATENT OFFICE.

KOSCOE D. SYKES, OF NORFOLK, VIRGINIA.

LUMBER DRIER.

Application filed February 24, 1923. Serial No. 620,961.

To all whom it may concern:

Be it known that I, KOSCOE D. SYKES, a citizen of the United States, residing at Norfolk, in the corporation of the city of 5 Norfolk and State of Virginia, have invented certain new and useful Improvements in Lumber Driers, of which the following is a specification.

This invention relates to new and novel 10 improvements in lumber drying apparatus, and is especially designed for the use of operators of portable saw-mills, who at present have no means of properly curing their products except by the use of cumbersome and expensive steam boilers and piping.

The prime object of the invention is to provide a simple, durable, economical and efficient apparatus adapted for the purpose 20 of properly drying and curing the products of portable saw mills.

Another object of this invention is to so construct the improved apparatus that the parts may be readily and easily disconnect- 25 ed, moved to a new location as desired and quickly reassembled.

A further object of the invention is to provide means in connection with the apparatus, constituting a sheet metal hood or 30 protector, which efficiently serves the double purpose, namely, first, to deflect any chips, lint, dust, bark or other substances which would be likely to fall on the hot radiator pipes and cause conflagration, second, to 35 more evenly diffuse the heat rising from the radiator and thus prevent the lumber nearest above the pipes becoming cracked or checked from the intense heat radiated from the pipes.

40 The foregoing and such other objects as may appear from the ensuing description are accomplished by the construction, arrangement, location and combination of the several parts hereinafter more fully described, illustrated by the accompanying drawings, and particularly set forth in the claims appended hereto, it being understood that slight changes in the proportions and minor details of the construction may be 45 resorted to without departing from the spirit or sacrificing any of the advantages of the invention.

In the accompanying drawings forming a part of this specification it will be seen 55 that:

Figure 1 is a side elevation of the appa-

ratus embodying my invention, with the metal hood or protector removed.

Figure 2 represents a plan partly in section, taken in the plane of the dotted lines 2—2, Fig. 1, looking in the direction of the arrows, with the hood or protector removed.

Figure 3 is a plan taken in the plane of the dotted lines 3—3, Fig. 1, showing the metal hood or protector in full lines and the heat radiating pipes in dotted lines, looking in the direction of the arrows, and

Figure 4 is a cross-section taken in the plane of the dotted lines 4—4, Fig. 3, looking in the direction of the arrows.

In the embodiment of my invention as illustrated, it will be seen that the numeral 5 designates the furnace, the brick wall of which is preferably about nine inches in thickness, 6 indicates the cast iron front of 75 the furnace having rearwardly extended flanges 7 formed therewith at each side thereof, 8 the channel irons or plates, and 9 a plurality of threaded bolts which are passed through the brick work of the furnace from side to side, through said flanges 7 and the channel irons or plates, the threaded end of each bolt being provided with a securing nut 10, whereby the said parts are fixedly secured, and thereby fastening the 80 furnace securely together. The numeral 11 indicates the cast iron furnace fuel feed door, 12 the ash clean-out and bottom draft door, and 13 the furnace damper formed of heavy sheet iron, with a rod 14 extending 90 entirely through the walls of the furnace and provided with a handle 15 at each end of said rod.

It will be perceived that the inner or rear end 16 of the furnace which projects into the drying or curing house, is formed with an arch to it, which is designed to take care of the tar and other waste matter which formerly had a tendency to clog up the old form of furnace, hence by this particular 95 formation the flame appears to completely burn and consume these by-products, and for the same reason the furnace is dropped below the level of the drying or heat radiating pipes, the front of said furnace being 100 approximately two feet below the grade, the numeral 17 designating the pit at the front of the furnace for the attendant or operator.

The drying or curing house 18 consists of 110 any suitable light frame portable structure which may be readily removed and reas-

sembled, and its interior is provided with a plurality of upright iron columns 19, properly spaced apart, and adapted to fixedly support the beams 20, said beams extending from one end of the structure to the other end, and secured to the upper face of each beam is a track 20', which runs entirely through the drier house, upon which track the lumber trucks 21 are supported and adapted to be passed into and out of the drier house from right to left or from left to right.

The heating or heat radiating system comprises a Y-shaped member 22 at its front end, formed of heavy sheet iron with its outer end fitted into the rear end of the furnace, each inner end of said member 22 being connected to one end of an outwardly and rearwardly inclined primary radiating pipe 23, the other end of each of the pipes 23 being connected to one end of an elbow member 24, and the other end of each elbow member is connected to one end of an inwardly and rearwardly inclined primary radiating pipe 25, the rear end of each pipe 25 being fitted to the inner ends of another Y-shaped member 26, the rear end of said member 26 being connected to the exhaust stack 27, formed of heavy sheet iron, suitably secured to the rear of the house, and provided with a damper 28, while the secondary radiator pipes 15' are fitted into cast iron collars 29, securely riveted to the pipes 23 and 25, with the squared ends of each pipe 15' projecting into the pipes 23 and 25 in order to receive its proper proportion of heat, and the central radiator pipe 30 extends from and connects the Y-shaped members 22 and 26, each end of said pipe 30 being passed through a cast iron collar 31, riveted to each Y-member, and projects into each member 22 and 26, in order that this pipe 30 may receive only its proportion of heat, approximately one-fourth. In each primary radiator pipe 23 and 25 near its forward end is fitted a suitable damper 32 by which the heat is controlled in the radiating system and shifted to either side of the system by the proper manipulation of these dampers. This entire heat radiating system is suitably supported upon a plurality of channel irons 33 which are fixedly secured in any desirable manner to the vertical iron columns 19.

It will be seen that each section of my improved heat radiating system comprising the pipes 23, 25, 15' and the elbows 24 are so constructed and connected together as to be readily interchangeable.

As clearly shown in Fig. 3, it will be seen that my entire heat radiating system is provided with a sheet metal hood or protector 34, which is fixedly secured to the beams 20, and extends above and along the entire length of each radiator pipe, in such a man-

ner that the hood will be suspended directly over, but not in contact with the radiator pipes. The said hood is formed by bending the metal sheets lengthwise, in the center, to an angle of ninety degrees and is reinforced or braced by having metal angle brackets 35 riveted to its lower sides. After being placed in position the several pieces are bolted or riveted together, thus forming a continuous hood or tent like structure, over the entire set of radiator pipes. Each hood is six inches wider than the pipe it covers and the form, when placed in position, is like a gable roof house, with the eaves extending beyond the pipes on each side thereof.

It will be readily obvious that the metal hood or protector is adapted to perform a double function, that is, it not only serves to deflect any chips, lint, dust, bark or other substances which would be likely to fall in contact with the hot radiator pipes and thus cause a conflagration, but it also serves to more evenly diffuse the heat rising from the radiator and prevent the lumber nearest above the pipes from becoming cracked or checked from the intense heat emanating from the heat radiating system of pipes.

It will also be evident that my construction of drier will readily permit the apparatus to be quickly disconnected, moved to a new location, and quickly reassembled, and that said apparatus is so constructed as to distribute the heat substantially over the entire area of the house, thus constituting an efficient means for the purpose intended.

Having thus described my invention what I claim and desire to secure by Letters Patent is:—

1. A lumber drier of the character described, comprising a house, a furnace located at the front of the house and having an arched rear portion projected into said house, a Y-shaped pipe member with its inner end fitted into said rear portion of the furnace, primary outwardly and rearwardly inclined heat radiating pipes having one end fitted into the outer ends of said member, primary inwardly and rearwardly heat radiating pipes with one end fitted into the inner ends of another Y-shaped member, elbow members connecting the other end of said primary pipes, and a plurality of secondary pipes connected to the primary pipes by cast iron collars riveted thereto.

2. A lumber drier comprising a portable house, a furnace located in a pit at the front of the house, said furnace being formed with an arched upper rear portion extended within said house, a damper fitted in said arched portion, a Y-shaped pipe member fitted within said rear portion, and a heat radiating system connected to said member within the house, all of said parts being so constructed

and connected that they may be readily disconnected, moved and reassembled.

3. A lumber drier of the character described, comprising a drying chamber or house, a furnace located at the front of the house with its rear upper end portion extended within said house, a Y-shaped member fitted within the rear portion of the furnace, an exhaust stack, a Y-shaped member connected to said exhaust stack, and a series of primary and secondary heat radiating pipes connected to said members and extended substantially over the entire horizontal area of the house.

4. A lumber drier of the character described, comprising a drying chamber, a furnace located at the front of the house with its rear end portion extended within said chamber, a Y-shaped member having one end fitted within said rear end portion and its other end connected with a plurality of primary heat radiating pipes, an exhaust stack, another Y-shaped member having one end fitted within said stack and its other end connected to a plurality of primary heat radiating pipes, means for connecting the meeting ends of said primary pipes, and a series of secondary heat radiating pipes connected to the primary pipes by a plurality of cast iron collars.

5. A lumber drier of the character described, comprising a drying house, a furnace outside the front of the house with its rear end portion extended within said house, a Y-shaped pipe member having one end fitted within said rear portion, and its other end connected with a plurality of primary heat radiating pipes, a damper fitted within each of said primary pipes, an exhaust stack provided with a damper, another Y-shaped member having one end connected to the stack and its other end fitted to a plurality of primary heat radiating pipes, means for connecting the meeting ends of said primary pipes, and a plurality of secondary heat radiating pipes connected with the primary pipes by a series of cast iron collars.

6. A lumber drier of the character described, comprising a drying house, a furnace at the front of the house with its rear

end portion projected within said house, and a heat radiating system within the house, consisting of a Y-shaped pipe member having one end fitted into the rear end of the furnace, an exhaust stack, another Y-shaped pipe member with one end fitted into said stack, and a series of intermediate pipes detachably connected to the other end of said members.

7. A lumber drier of the character described, comprising a house, a furnace having its rear end extended within the house, lumber truck supporting beams extending through the house, means for supporting said beams, a heat radiating system within the house consisting of a Y-shaped member having one end fitted within the furnace, an exhaust stack, another Y-shaped member with one end fitted into the stack, a series of pipes detachably connected to and between the other end of said members, and means fixedly secured to said beam supporting means for supporting said heat radiating system.

8. A lumber drier of the character described, comprising a house, a furnace having its rear end projected within the house, beams extending through said house, means for supporting said beams, a heat radiating system within the house and connected with the furnace, means fixedly secured to said beam supporting means for supporting said heat radiating system, and a continuous hood protector fixedly secured above and overlapping said system adapted to prevent conflagration and at the same time more evenly diffuse the heat rising from the said system.

9. A lumber drier of the character described, comprising a house, a furnace located at the front of the house with its rear end extended within the house, beams fixedly supported and extending through the house, an exhaust stack connected with the house, a heat radiating system connected with said furnace and stack, and a continuous metallic hood protector fixedly suspended immediately above and overlapping said system adapted to more evenly diffuse the heat arising from the system and to prevent conflagration.

KOSCOE D. SYKES.
